G. W. FERDON.

GARBAGE CAN.

APPLICATION FILED JAN. 26, 1920.

1,353,127.

Patented Sept. 14, 1920.

UNITED STATES PATENT OFFICE.

GUY W. FERDON, OF CRESSKILL, NEW JERSEY.

GARBAGE-CAN.

1,353,127.

Specification of Letters Patent. Patented Sept. 14, 1920.

Application filed January 26, 1920. Serial No. 354,186.

To all whom it may concern:

Be it known that I, GUY W. FERDON, a citizen of the United States, residing at Cresskill, in the county of Bergen and State 5 of New Jersey, have invented certain new and useful Improvements in Garbage-Cans, of which the following is a specification, reference being had therein to the accompanying drawing.

10 This invention relates to garbage cans, or to receptacles for holding garbage, ashes, trash or other refuse to await removal at infrequent intervals.

15 My object is to produce a can of this kind which is simple in construction, strong and durable, which can not easily be injured by the slamming about and abuse of the average garbage man, on which is secure against the molestations of foraging 20 animals, one which can be readily opened by the foot or by one hand, and one which may be tightly closed to keep refuse from the attacks of insects, from emitting foul odors and from leakage and one which 25 has no loose or easily detached parts to become lost, thus rendering the device more or less inefficient.

In the drawings:—

Figure 1 is a perspective view showing 30 my garbage can or pail with its lid down.

Fig. 2 is a side sectional view, showing the same device with the lid in substantial upright position.

Fig. 3 is a side view, on a smaller scale, 35 of the complete can device.

In the drawing which represents my pail, which is of the usual cylindrical type, with rear handle 2 and provided with a bail 3 secured by ears 4 to the sides of the pail. 40 This bail is substantially semi-circular in shape and is of a radius large enough to clear the sides of the can and drop down. At 5 I show a hinge by means of which the lid 6 is hinged to the can. This hinge is 45 placed by preference half way between the ears 4 and is substantially at an angle of 90° from each of the ears 4. Diametrically opposed from said hinge 5, or preferably diametrically opposed, I provide a spring 50 clip 7 hinged to the body of the can at 8 so that it may be turned down to free the lid or turn up to engage the top of the lid. This clip is provided with an up-turned portion 9 below which a finger, or the toe 55 of a shoe for that matter, may be inserted, so as to lift the clip off and away from the

can. At some place on the forward part of the lid and preferably near the clip 9 I secure a loop 10 and in this loop I hinge one end of a rod 11. This rod or bar 11 60 is loose in the loop 10 and is long enough to engage the topmost part of the bail 3 when the latter is in its vertical position. This length may be varied a little and the length may be long enough to engage the 65 bail when the lid occupies such a rearwardly tilted position as shown in Fig. 3 so that pressure upon the bail in a vertical direction will cause the bail to turn backward over the hinge. Pressure obliquely 70 directed against the rod or against the bail will also tend to raise the lid. The rod 11 is loose on the bail so that though its path of movement about its loose connection to the lid does not coincide with the curve of 75 the bail throughout, yet there is a certain amount of sliding relation or play upon the bail, so that while the fingers can be made to stride the rod, the rod can be pushed to one side or the other when the 80 pail is lifted by the handle. This is of especial advantage in very cold weather, when the person who handles garbage often wears mittens rather than gloves. The bail and link might be arranged so that the bail 85 would be inclined forward, but this would make the device somewhat awkward to use.

In operation the clip 9 is turned back by means of the fingers or thumb of one hand or the toe of a foot, if necessary, as 90 shown in Fig. 2 and the bail or handle is pressed downward or to the rear, the bail, in response to this pressure, by means of the link or bar 11 lifts the forward part of the lid and the can is opened for permitting access to its interior. A person using this can can open the lid with one hand, standing behind the lid when it is in the position shown in Fig. 2 so that the clothes will be shielded from dirt or garbage while 100 depositing or emptying the trash of whatever kind he carries into the receptacle and closing the lid and the device is kept secure from the access of insects or animals and also sealed against the escape of odors 105 or poisonous gases. The device while especially intended for the reception of garbage is also useful for the reception of ashes, in which case the lid when in the position shown in Fig. 2 is especially useful as a shield or 110 guard.

It is not necessary that the clip 9 should

in all cases be turned down on the cover but it is better and safer, especially at night, when a garbage can is left in the open, to turn this so as to hold the lid in position. 5 When this is in position it will be found that access by dogs or other marauding animals to the contents of the can is impossible. The can may be tipped over, rolled sidewise, turned upside down, or otherwise abused 10 without permitting any of the contents to escape unless it be a slight leakage of liquid.

Moreover my can is strong and simple in construction and not liable to get out of order. It can readily stand the abuse which 15 garbage collectors are apt to subject such utensils to.

When the can is shipped I usually ship it partly knocked down or at least with the link or rod free from engagement with the 20 bail, as this facilitates packing. If desired the bail itself may also be shipped separate from the can, but this is hardly necessary. The dealer in setting up his stock simply causes the link or rod to engage or snap over 25 the bail and of course the can may be of any shape desired. The link or rod may also be made so that it can be readily unhooked from the cover, or it may be made removable from both bail and cover.

30 It will be seen that I can lift the cover just a little if I wish to slide some small object into the can and then push it down again. I can also lift it as shown in Fig. 2 or I can turn it clear back so that the whole top of 35 the can is completely open for cleaning or for other purposes. By the arrangement here shown my cover never becomes lost and is never in the way.

In some cases and for some uses I may 40 omit the engaging clip entirely, for instance when the device is used only as an indoor or sink receptacle; and refuse therefrom emptied into a larger container to be taken outdoors or elsewhere. In use in this manner the bail and link or rod keep the cover 45 closed.

I may also make said clip stiff or inelastic and I may have more than one. I may place

it on the lid instead of the can and I may do any equivalent thing. 50

When the rod or bar is detached from the bail in shipping it lies flat on the lid and when detached from the lid it swings downward with the bail and lies alongside the can. If detached from both it may be placed 55 within the can.

As indicated I find that by having the bail collapsible, as it were, I may ship my cans with smaller cans nested within them if need be, and thus effect a still further saving in 60 shipping and storage space and in drayage.

Having thus described my invention, what I claim as new and desire to secure by Letters Patent, is:—

1. In a garbage can, in combination, a 65 cylindrical pail, a bail semicircular in shape and of greater radius than the pail, pivoted to the pail at diametrically opposite points, a circular lid hinged to the pail so as to be capable of turning back over the pail at a 70 point midway between the pivot points of the bail and a removable link loosely pivoted to the lid forward of the plane of the bail when upright, said link extending to the upper part of the upright bail and loosely and 75 slidably connected thereto, whereby side or downward pressure upon the link or the bail effects the moving of the lid upon its hinge to open and close the pail and whereby the pail may be lifted or moved by a mittened hand.

2. In a garbage can, in combination, a pail, a bail, a lid hinged to said pail, a link having a loose connection with the lid and a loose and sliding connection with the bail, 85 the construction being such that the lid may be raised to any angle or turned back completely, and a spring clip having toe engaging means arranged on the pail to take over the lid and to hold the lid securely down, 90 the clip being arranged as near as possible to the link whereby the clip may be swung back and the link pressed rearwardly by hand or foot with relatively little movement.

In testimony whereof, I affix my signature. 95
GUY W. FERDON.
